UNITED STATES PATENT OFFICE.

MILTON B. HATCHER, OF AUGUSTA, GEORGIA.

TOBACCO-PLIERS.

SPECIFICATION forming part of Letters Patent No. 499,539, dated June 13, 1893.

Application filed October 19, 1892. Serial No. 449,349. (No model.)

To all whom it may concern:

Be it known that I, MILTON B. HATCHER, of Augusta, in the county of Richmond and State of Georgia, have invented a new and 5 useful Improvement in Tobacco - Pliers, of which the following is a full, clear, and exact description.

The object of my invention is to provide a simple and convenient implement for the removal of plug or slab tobacco from the box, and consists in the construction and combination of parts, as is hereinafter described and claimed.

Reference is to be had to the accompanying 15 drawings forming a part of this specification, in which similar letters of reference indicate corresponding parts in all the figures.

Figure 1 is a perspective view of the implement. Fig. 2 is a longitudinal, broken and 20 partly sectional view of the front portion of the device, showing the parts in open adjustment; and Fig. 3 is a side view of the forward part of the tool, partly in section and in closed adjustment.

25 There are two limbs A, B, provided that form main portions of the implement. The limb A is widened forwardly and this portion is longitudinally and vertically slotted at the transverse center from the front end a proper

30 distance, thereby producing two parallel jaws *a* of equal length. From the point *b* where the jaws *a* join the other portion of the limb A, this latter part is prolonged and bent as shown, to provide a bow handle piece. The

35 other limb B is made of such a relative thickness forwardly, as will permit its introduction between the jaws *a* and subsequent pivoting thereto at *c*, thereby connecting the members A, B, loosely. The limb B is bent

40 at *e* and also at *g* above and below the jaws *a*, so as to project a portion *B'* forwardly above the jaws, the remainder, or part that extends rearwardly from *g*, forming a handle bar that is mainly straight, but slightly curved

45 at the free end *h* away from the handle piece of the limb A, thereby avoiding contact with the latter. There is a curved rack *i* formed on or secured to the portion *B'* of the limb B, a short distance from the forward end of said

50 part and which projects downwardly between the jaws *a*. Portions of the jaws *a* project

in advance of the rack *i* and afford support for a rocking toe which consists of a circular hub *m* that is centrally pivoted between the jaws on a transverse pin *n*, and has a series 55 of teeth *m'* formed on it that are in meshed engagement with the rack teeth, and is further provided with a curved sharpened toe *n*² which is joined to the hub by an arm *n'* at its rear end. The toe *n*² curves forwardly 60 and upwardly, having its free end portion rendered wedge-shaped by converging its top and bottom sides.

There is a tooth like projection *o* formed on the front end of the jaw portion *B'*, toward which the toe *n*² will be moved so as to nearly impinge on it when the handle pieces of the limbs A, B, are vibrated toward each other, these parts being held normally separated by the spring *p* that is fastened by one 70 end to the handle piece of the limb A and presses its free end on the handle piece of limb B, as shown in Fig. 1.

When the implement is to be used to remove plugs or slabs of chewing tobacco from 75 the packing box wherein the tobacco is tightly embedded, the operator grasps the instrument, and by an insertion of the free sharp end of the toe *n*² between an end of a plug or slab and the inner side of the box, gets a purchase 80 on the tobacco slab. The handles of the implement are now tightly gripped so as to rock the toe *n*² toward the tooth *o*, which will cause the plug or slab of tobacco to be firmly interlocked between the rocking toe and forward terminal of the limb B and toe *o*, and 85 will permit the tobacco to be quickly removed from the box by manipulating the implement. When the pliers are not in use the pressure of the spring *p* will spread the limbs 90 A, B, sufficiently to throw the toe *n*² below the jaws *a*, with its free sharp end extended in front of the latter; a contact of the rear end of the toe upon the lower end of the rack *i*, as at *i'* in Fig. 2, serving to limit the divergence 95 of the handle piece of the limbs, and of their forward portions also, the parts assuming the relative positions shown in Figs. 1 and 2.

Having thus fully described my invention, 100 I claim as new and desire to secure by Letters Patent—

1. A tobacco pliers, comprising two handle members crossed and pivoted near their outer ends, the said members in front of their pivot *c* being of approximately the same length, 5 and a tooth pivoted to the forward end of one member in front of the pivot *c* to swing outwardly and inwardly toward and against the front end face of the other member and geared to the latter member in front of said pivot *c*, substantially as set forth.
2. The herein described tobacco pliers, comprising the two handle members A B, pivoted and crossed near their outer ends and of approximately the same length in front of their pivot *c*, the extension B' having a depending 15 rack *i* between its pivot and front extremity, and the curved tooth pivoted to the outer end of the extension *a* of the member A to swing outwardly and inwardly at its point toward 20 and against the front end face of the extension B' and provided at its pivoted end with a toothed segment *m* meshing with said rack, substantially as set forth.
3. The herein described pliers, comprising 25 the pivoted cross members A B, a tooth or lug *o*, on the forward extremity of the outer end B' of the member B, a rack *i* on the under side of the end B', and the curved tooth pivoted to the outer end of the member A to 30 swing toward and contact with the forward extremity of the end B' under its tooth or lug *o* and having a toothed segment meshing with said rack, substantially as set forth.
4. In tobacco pliers, the combination with a limb slotted centrally at its forward end, 35 and a second limb pivoted between the jaws produced by said slot, and a spring between the limbs normally holding them apart, of a depending curved rack formed on one of said limbs, and a curved toe pivoted between the 40 jaws of the other limb and having teeth adapted to engage with and be rocked by the rack, substantially as described.
5. In tobacco pliers, the combination with a limb having a curved handle piece at one 45 end, and centrally and longitudinally slotted at its other end, thereby forming parallel jaws, and a second limb pivoted between said jaws and bent to dispose its forward part above the jaws and produce a handle piece 50 below said jaws, of a curved rack formed on the bent limb, and depending from its forward end, a rocking toe having a hub pivoted between the jaws in advance of said rack, a series of teeth on said hub meshing with the 55 rack teeth, and a spring between the handle pieces of the limbs, normally holding said limbs apart, substantially as described.

MILTON B. HATCHER.
